DESIGN FOR A CASING FOR FURNACES AND STOKERS

John Gordon Rideout, Cleveland, Ohio, assignor to Iron Fireman Manufacturing Company, Portland, Oreg.

Application June 30, 1939, Serial No. 85,786

Term of patent 14 years

To all whom it may concern:

Be it known that I, John Gordon Rideout, a citizen of the United States, residing at Cleveland, county of Cuyahoga, State of Ohio, have invented a new, original, and ornamental Design for a Casing for Furnaces and Stokers, of which the following is a specification, reference being had to the accompanying drawings, forming part thereof.

Fig. 1 is a perspective view from the left front corner of the stoker, showing my new design.

Fig. 2 is a perspective view from the right front corner of the stoker.

The other side of the casing is substantially plain.

I claim:

The ornamental design for a casing for furnaces and stokers, as shown and described.

JOHN GORDON RIDEOUT.
